[57] CLAIM

The ornamental design for a LED traffic signal light, as shown and described.

DESCRIPTION

FIG. 1 is a perspective view of a LED traffic signal light in accordance with the present invention;

FIG. 2 is a front view thereof;

FIG. 3 is a side elevational view thereof, the opposite side view being a substantial mirror image thereof and the top and bottom views being substantial mirror images thereof;

FIG. 4 is a rear view thereof;

FIG. 5 is a front view of an alternative embodiment of the present invention;

FIG. 6 is a side elevational view of the embodiment of FIG. 5, the opposite side view being a substantial mirror image thereof and both the top and bottom views being substantial mirror images thereof; and,

FIG. 7 is a rear view of FIG. 5.
